UNITED STATES PATENT OFFICE.

FREDERICK J. LOCKWOOD, OF BRIDGEPORT, CONNECTICUT.

REIN-HOLDER.

SPECIFICATION forming part of Letters Patent No. 395,156, dated December 25, 1888.

Application filed September 27, 1888. Serial No. 286,530. (No model.)

To all whom it may concern:

Be it known that I, FREDERICK J. LOCKWOOD, a citizen of the United States, residing at Bridgeport, in the county of Fairfield 5 and State of Connecticut, have invented certain new and useful Improvements in Rein-Holders; and I do hereby declare the following to be a full, clear, and exact description of the invention, such as will enable others 10 skilled in the art to which it appertains to make and use the same.

My invention has for its object to produce a device of this class in which the number of parts and the cost of production shall be reduced to the minimum, which shall be always 15 ready for use, practically impossible to get out of repair, and which shall be so constructed as not to catch the reins or be in the way when not in use, an important feature in devices of this class being to secure a simple 20 and perfectly-working device which may be manufactured so cheaply that a fair profit may be realized, while at the same time the device may be retailed at a very low price, 25 thus placing it within the reach of all. With these ends in view I have devised the simple and novel construction of which the following description, in connection with the accompanying drawings, is a specification, numbers 30 being used to denote the several parts.

Figure 1 is a side elevation, the parts of the clamp being separated; Fig. 2, a side elevation showing the manner in which the device is attached and used; and Fig. 3, a front 35 elevation thereof, as in use.

The device, as a whole, consists of two spring-arms, which in practice I make of either steel or brass, and an ordinary simple clamp, the parts of which are cast. The 40 device is so constructed that it may be attached or detached in an instant's time, and may be placed upon any portion of the vehicle most convenient—as, for example, upon the dash-board or upon the seat. When 45 placed upon the dash-board, it may be placed at the right-hand corner, close by the whip, and thus be entirely out of the way in driving. The parts, moreover, are so constructed that it is practically impossible to catch the 50 reins except when they are intentionally placed between the spring-arms, as shown in Figs. 2 and 3. For convenience in illustra-

tion I have shown the device as attached to a dash-board. The portion of the body of the clamp carrying the spring-arms may of course be placed in either the inner or the outer side, as may be most convenient.

1 denotes the dash-board, and 2 and 3 denote, respectively, the parts of the clamp.

4 denotes the spring-arms, the lower ends 60 of which are rigidly secured to one of the parts of the clamp. In practice I preferably provide this part of the clamp with a solid projection, 5, (see dotted lines, Figs. 1 and 2,) and secure the lower ends of the arms thereto 65 by rivets 6, passing through said arms and the projection. In practice the arms are placed at a sufficient distance apart to receive readily an ordinary pair of reins. They are furthermore curved inward slightly, the upper ends being curved outward and over, so that the reins may be inserted and removed without difficulty, and will be held firmly. In the drawings I have shown the arms as attached to part 2 of the clamp.

7 denotes a screw, which passes freely through part 3 and engages a correspondingly-threaded opening. (See dotted lines in part 2.) The head of this screw is preferably countersunk into part 3, so as to be wholly 80 out of the way, and not likely to become detached in use. In practice I preferably provide one of the parts with a pin, 8, which engages a corresponding hole, 9, in the other part, (see dotted lines, Figs. 1 and 2,) for the 85 purpose of keeping the jaws in line with each other.

I also provide at the upper end of one of the parts of the clamp a flange, 10, which engages the other part, but allows the jaws of the clamp to swing inward toward 90 each other, thereby grasping the dash-board or seat firmly when the screw is tightened up. In use the reins are simply forced down between the spring-arms, as shown in Figs. 2 and 3. The arms are made sufficiently elastic, 95 so that they will yield readily when the reins are pressed between them, and at the same time of sufficient strength to hold them there firmly, so that they are not liable to be thrown out by any accident or by the switching of a 100 horse's tail.

Having thus described my invention, I claim—

A rein-holder consisting of the combina-

tion, with a clamp composed of the parts 2 and 3, the former being provided with the solid projection 5 and pin 8, and the latter having the hole 9, flange 10, and attaching-screw 7, of the spring-arms 4, rigidly secured at their lower ends to the said projection and outwardly and downwardly curved at their upper ends, as shown, so that the reins may be readily inserted and removed, and will be

held in any portion of the arms whether inserted single or double.

In testimony whereof I affix my signature in presence of two witnesses.

FREDERICK J. LOCKWOOD.
